The ornamental design for a lug receiver for a drum, as shown and described.

DESCRIPTION

FIG. 1 is a perspective view of a lug receiver for a drum showing my new design;

FIG. 2 is a top plan view thereof;

FIG. 3 is a left side elevational view thereof, the right side being a mirror image of the left;

FIG. 4 is a front elevational view thereof;

FIG. 5 is a rear elevational view thereof; and

FIG. 6 is a bottom plan view thereof.
